UNITED STATES PATENT OFFICE.

FREDERICK E. STRASBURG, OF RUMFORD FALLS, MAINE, ASSIGNOR TO
CONTINENTAL PAPER BAG COMPANY, A CORPORATION OF MAINE.

CUTTING MECHANISM.

No. 810,993.

Specification of Letters Patent.

Patented Jan. 30, 1906.

Application filed May 4, 1905. Serial No. 258,820.

To all whom it may concern:

Be it known that I, FREDERICK E. STRASBURG, a citizen of the United States, residing at Rumford Falls, in the county of Oxford 5 and State of Maine, have invented certain new and useful Improvements in Cutting Mechanism, of which the following is a specification.

This invention relates to cutting mechanism, particularly to that class of such mechanism as is employed for severing a continuous web of paper into blanks or sections of uniform and predetermined length.

In the drawings accompanying this specification is illustrated a machine embodying one form, and which may be the preferred form, of my invention.

In the drawings, Figure 1 is a plan view of said machine. Fig. 2 is a side elevation corresponding with Fig. 1, but with the driving-pulley removed. Fig. 3 is an enlarged plan view of details of the severing mechanism; and Fig. 4 is a sectional elevation corresponding to Fig. 3, the section being taken on line 25 *a a* therein. Fig. 5 is a rear view of a portion of one of the serrated knives. Fig. 6 is a cross-section of float F on line *b b* of Fig. 4.

My invention is peculiarly applicable in connection with paper-bag machines in which it is desired to sever a continuous paper tube into lengths suitable for bag-blanks. Such paper tube may be a simple flat tube, or said tube may be provided with an inwardly-folded tuck in each side thereof. My improved 35 mechanism is also adapted for severing continuous webs, tubular or otherwise, having other forms of cross-section or for severing flat continuous single, double, or multiple webs and all of the plies of which may pass 40 above the float or part above and part below.

It is particularly desirable in severing paper tubing into bag-blank sections to provide at the forward end thereof a difference in length of the upper and lower plies, so that 45 one ply may be gripped by the bag-bottom-forming mechanism without involving the other ply. Preferably the upper ply of the tubular blank is the shorter, whereby the lower ply is allowed to project in front thereof. This provides at the other end of the blank, and which other end is later the mouth of the finished bag, a rearwardly-extending lip on the upper ply, whereby the bag-mouth may be conveniently opened for use. My

improved machine provides for the formation in severing, on the ends of each section thereof, of projecting portions, as described. 55

In order to obtain good results in a rotary cutting mechanism for tubular paper webs, it is desirable, first, to have the cutting edge of 60 the rotating serrated knife travel at a considerably greater linear speed than that of the web to be cut; second, to have the circle described by the cutting-knife of a relatively small diameter, so as to have the distance 65 traveled by said knife in engagement with the stationary float relatively short. The first feature is desirable so that the tubular web may be severed with certainty and completeness and without connecting-filaments remaining between the web and the severed section. 70 The second feature is desirable so that the rotating cutter may upset as little as possible the rear end of the severed blank as said cutter swings out of engagement with the 75 float.

Heretofore in rotary cutting devices the paths of the rotating knives have each had a circumference equal to or nearly equal to the length of the blank that it was desired to 80 sever, and when a different length of blank was desired it was necessary to change the diameter of the paths of the rotating knives to correspond. In my improvement such change in diameters is unnecessary, as a simple change in gearing is all that is necessary. 85

The machine illustrated in the drawings comprises side frames 2 3, in which may be supported the various parts of the mechanism. These side frames may be secured in 90 suitable relation to each other by tie-frames 4 5, extending therebetween and fastened at their ends, respectively, to said side frames by bolts, as 6.

At F in the right-hand or entering end of 95 the machine is shown the delivery end of some suitable tube-forming mechanism. This member F is in the nature of a float and is of suitable width to pass through an opening between feed-rolls 7 8. This opening is formed by oppositely-disposed reduced portions, as 9, in said rolls. Float F lies within and is surrounded by the paper tube which it is desired to sever. If said tube is provided with inwardly-folded tucks, said tucks are preferably disposed below the float. My improved 100 machine is provided with two pairs of feed-rolls 7 8 and 11 12, respectively, and which

two pairs of rolls are driven at the same surface speed from pulley 10 by means of suitable gearing. This gearing is as follows: Turning freely upon stud 13, which stud projects outwardly from frame 2, is driving-gear 14. Pulley 10 is fast to hub 15 of gear 14, and through said pulley said gear may be driven. Rolls 7 8 are fast to and supported for revolution upon shafts 17 18, respectively, and which shafts are provided with suitable bearings in brackets 16 19, upstanding from frames 2 3, respectively. Shafts 17 18 are provided with intermeshing gears 21 22. Rolls 11 12 are fast to and supported for revolution upon shafts 23 24, respectively, and which shafts are provided with suitable bearings in brackets 26 27, upstanding from frames 2 3, respectively. Shafts 23 24 are provided with intermeshing gears 20 25, respectively, and lower gear 25 is engaged by driving-gear 14. On adjustable stud 28 is gear 29, and on adjustable stud 30 is gear 31. Gear 29 meshes with driving-gear 14, and fast on shaft 32, mounted for rotation in frame 2, is gear 33. Said gear 33 meshes on the one side with gear 29 and on the other side with gear 31. On stud 34, projecting outwardly from frame 2, is rotatably mounted gear 35. Said gear 35 meshes on the one side with gear 31 and on the other with gear 22 of feed-roll 8. By the gearing just described the two sets of feed-rolls 7 8 and 11 12, respectively, may be driven to feed the web of paper in the direction of arrow A.

In bracket 36, secured to brackets 16 19 by suitable bolts, as 37, are mounted cutter-shafts 38 39. These shafts are geared together by equal gears 40 41, respectively, and which gears for convenience are situated at those ends of their respective shafts adjacent to frame 3. On the inboard end of shaft 32 is fixed gear 42, meshing with gear 43 on lower cutter-shaft 39. Gear 42 has teeth thereon only throughout a portion of its periphery and whereby gear 43 is intermittently driven. Also gear 43 has a stop-face 44 for engagement with that portion 45 of the periphery of gear 42 which is unprovided with teeth for holding gear 44 against rotation when so engaged. By the means just described shafts 38 39 may be revolved one revolution each during a portion of the revolution of gear 42 and then held at rest during the remainder of the revolution of that gear.

After passing between rolls 7 8, float F is widened out to occupy substantially the whole width of the inside of the tubular web. In the upper face of said float in a line directly below and parallel with shaft 38 is provided a series of contiguous grooves 46 thereacross. These grooves are preferably V-shaped in cross-section and may be formed by milling with a cutter of somewhat larger diameter than that of the circle described by the rotation of the cutting edge of serrated knife 50,

or said grooves may be formed by other means and have other longitudinal profiles, respectively, than that of a circle. Shaft 39 is preferably located a short distance in the direction of travel of the web to be cut beyond shaft 38, and in the bottom face of float F, directly above and parallel with shaft 39, is a series of contiguous grooves 56 thereacross, similar in every way to grooves 46 in the upper face of said float. Grooves 56 are offset laterally from grooves 46 a distance equal to one half their pitch or distance from one another, so that the upper and lower grooves will not cut into one another, and thereby unduly weaken the float. (See Fig. 6.) Shafts 38 39 are of such size and so located with reference to each other that float F has sufficient space to pass therebetween; but said float preferably stands free of said shafts, so as to allow unobstructed travel of the paper web as it moves forwardly about the float.

Shaft 38 is cut away lengthwise thereof on one side at 47 for the reception of serrated knife 50. In the present instance face 47 is shown as curved lengthwise; but any other desired profile may be used. Said knife 50 conforms to the profile of face 47 and may be secured to shaft 38 by any convenient means, such as screws 48, engaging with slots, such as 49, in the knife and threaded into said shaft. The cutting edge of said knife conforms to the periphery of a cylinder having a diameter slightly in excess of that of shaft 38. Thus the points 51 of the edge of said knife are enabled to engage slots 46 in the upper face of float F. On knife 50 there is a cutting-point 51 for each slot in the face of the float, whereby a continuous cutting-line is maintained entirely across said upper face of the float F. Shaft 39 is cut away similarly to shaft 38; but in the present instance face 490 of the cut-away portion of said shaft 39 conforms to a plane. Secured to said face 490 is knife 60, whose cutting edge 61 in the present instance conforms to a straight line parallel with the axis of said shaft 39. It is obvious that other profiles of face 490 and edge 61 could be substituted for the straight line illustrated. Knife 60 is secured to shaft 39 by screws 52, and the path of its cutting edge conforms to the periphery of a cylinder having a diameter slightly in excess of that of shaft 39, whereby points 61 are enabled to engage slots 56 in the under face of float F. Said points 61 and slots 56 are equal in number and equally spaced, whereby a continuous cutting-line is maintained entirely across the under face of the float. Shafts 38 39 are so timed in relation to each other that the ends of the cutting edge 61 of cutter 60 rotate directly in advance and closely contiguous to the ends, respectively, of curved cutting edge 51 of knife 50. By this arrangement the tubular web may be severed with certainty and precision at its edges. Knives

50 60 normally stand with their cutting edges pointed upwardly and downwardly, respectively, as shown in Fig. 2.

As illustrated, the relative sizes of gears 42 5 43 are such that gear 43 revolves once during about one-quarter of each revolution of gear 42 and remains at rest during about three-quarters of each revolution thereof. Also the relative speeds of gear 43 and rolls 7 8 and 10 11 12 are such that knives 50 60 while running travel at a linear speed about fifty per cent. greater than that of the paper web to be severed. By increasing the diameter of gear 33 the paper web will be fed faster relative to 15 the operation of the cutting mechanism, and longer blanks or sections will therefore be severed. By decreasing the diameter of said gear the paper web will be fed slower relative to the operation of the cutting mechanism, 20 and shorter blanks will therefore be severed. Intermediate gears 29 31 are shiftably mounted, as hereinbefore described, to accommodate changes in the diameter of said gear 33.

In studs 53 54, projecting from brackets 25 26 27, respectively, is supported shaft 55. On said shaft is fixed table 62, which assists the paper web into engagement with rolls 11 12 and thence out of the machine. Said table is cut away at 560 to allow high portions 30 57 of roll 11 to engage corresponding high portions of roll 12 for the feeding of the paper web.

The operation of my improved machine is as follows: Suitable paper tubing, either with 35 or without inwardly-folded tucks, being delivered around float F, is led forward between rolls 7 8 and thence between shafts 38 39 and beyond the end F² of float F onto table 62 and into the grip of rolls 11 12. If tubing having 40 an inwardly-folded tuck in each side thereof is used, said tubing may be fed into the machine with the tucks either above or below the float; but when my improved machine is used in connection with paper-bag machinery 45 it is customary and desirable to dispose the tucks under the float. The machine is then started in the direction indicated by the arrow on pulley 10. The paper web is fed forward until the leading tooth 420 of gear 42 50 engages stop 430 of gear 43, whereby said gear 43 is started rotating, and knives 50 60 are thereby revolved to engagement with grooves 46 56, respectively, of float F. Knife 50 in swinging into grooves 46 presses the 55 upper ply of the paper tube down into said grooves 46, thereby successively puncturing and substantially severing said upper ply throughout the entire width thereof, commencing first at its outside edges, and thence 60 toward and at the middle thereof. Furthermore, by means of the excess speed of knife 50 over that of the paper that portion of the paper directly in advance of the knife is pushed forward, and any remaining portions 65 thereof which may be still joined to that por-

tion of the paper rearward of the knife are therefore broken therefrom and the severance completed. The relatively short radius of rotation of cutting edge 51 of knife 50 enables it to swing promptly out of engagement 70 with the paper, whereby upsetting of the rear end of the severed section is prevented. Directly succeeding the commencement of the operation of knife 50, just described, knife 60 on shaft 39 rotates against the lower ply of 75 the tubular web and passes into engagement with slots 56 in the under face of float F just in advance vertically of the ends of blade 50. The operation of said knife 60 is the same in all respects as that of knife 50, except as 80 knife 60 has its cutting edge in a straight line all of its teeth 61 will enter the paper simultaneously. Knife 60 thus penetrates and severs the lower ply of the tubular web, including the inwardly-folded tucks therein, 85 and by the combined action of knives 50 60 said tubular web is entirely severed. The operation is thus completed, and the severed section is conducted away over table 62 by means of rolls 11 12. 90

I claim—

1. The combination of a float having a plurality of laterally-contiguous grooves lengthwise in the face thereof, an intermittently-rotatable knife contiguous to the float, said 95 knife having a plurality of teeth for engagement with the grooves respectively, in the float, all combined and working together substantially as described.

2. The combination of a float having a plurality of laterally-contiguous grooves lengthwise in the face thereof, an intermittently-rotatable knife contiguous to the float, said knife having a plurality of teeth for engagement with the grooves respectively in the 100 float, means to feed a web between the float and knife, means to intermittently rotate the knife at a linear speed greater than the feed of the web all combined and operating together substantially as described. 110

3. The combination of a float having a plurality of laterally-contiguous grooves lengthwise in each side thereof, said grooves being sufficient in number to extend substantially the width of each side of said float, a rotatable knife above the float, said knife having a plurality of teeth for engagement with each of the grooves respectively in the upper face of the float, a rotatable knife below the float, said knife having a plurality of teeth for engagement with each of the grooves respectively in the under face of the float, means to feed a web around the float and between the float and the knives and means to rotate the knives intermittently and at a linear 115 speed greater than the feed of the web. 120

4. The combination of a float having a plurality of laterally-contiguous grooves lengthwise in each face thereof, said grooves being sufficient in number to extend substantially 130

- the width of each face of the float, said grooves in the upper face of the float being longitudinally substantially opposite the grooves in the lower face of the float and spaced laterally intermediate thereof respectively and none of said grooves perforating said float; a rotatable knife above the float, said knife having teeth for engagement with each groove respectively in the upper face of the float and a rotatable knife below the float, said knife having teeth for engagement with each groove respectively in the lower face of the float, all combined and operating together substantially as described.
- 15 5. The combination of a float having a plurality of grooves lengthwise in each face thereof, said grooves in the upper face of the float being longitudinally substantially opposite the grooves in the lower face of the float and spaced laterally intermediate thereof respectively; a rotatable knife above the float, said knife having a plurality of teeth for engagement with the grooves respectively in the upper face of the float, and a rotatable knife below the float, said knife having a plurality of teeth for engagement with the grooves respectively in the lower face of the float; and means to intermittently rotate the knives, all combined and operating together substantially as described.
- 20 6. The combination of a float having a plurality of laterally-contiguous grooves lengthwise in the face thereof, a rotatable knife above the float, said knife having a plurality of teeth for engagement with the grooves respectively, in the float, means to feed a web over the float and under the rotatable knife,
- 25
- 30
- 35

means to normally hold the knife out of engagement with the float, means to intermittently rotate the knife at a linear speed in excess of the feed of the web, all combined and operating together substantially as described. 40

7. The combination of a float having a plurality of laterally-contiguous grooves lengthwise in the face thereof, a rotatable knife above the float, said knife having a plurality of teeth for engagement with the grooves respectively in the float, means to normally hold the knife out of engagement with the float and means to intermittently rotate the knife, all combined and operating together 45 50 substantially as described.

8. The combination of a float having a plurality of grooves lengthwise in each face thereof, said grooves in the upper face of the float being longitudinally substantially opposite the grooves in the lower face of the float and spaced laterally intermediate thereof respectively and none of said grooves perforating said float; a rotatable knife above the float and a rotatable knife below the float, each knife having teeth for engagement with the grooves respectively in the float, all combined and operating together, 55 60 substantially as described.

Signed at Rumford Falls, Maine, this 1st day of May, 1905, in the presence of two subscribing witnesses.
